UNITED STATES PATENT OFFICE.

OWEN OSBORNE, JR., OF PHILADELPHIA, PENNSYLVANIA.

UNDERHOSE.

Application filed April 28, 1925. Serial No. 26,556.

To all whom it may concern:

Be it known that I, OWEN OSBORNE, Jr., a citizen of the United States, and a resident of Philadelphia, in the county of Philadelphia and State of Pennsylvania, have invented a new and Improved Underhose, of which the following is a full, clear, and exact description.

This invention relates to underhose and more particularly to a hose or stocking which is designed to be worn under a silk outer hose.

When the weather is cold it is desirable to wear under a silk stocking an underhose which will provide the necessary warmth. Such underhose as heretofore made are constructed without sole, toe and heel portions and have straps holding the upper portion of the foot of the hose in place. Such straps slip particularly when they are not a perfect fit, and other forms of construction are undesirable principally for the reason that either they do not properly hold the underhose or that they are uncomfortable and too warm for that portion of the foot within the slipper or shoe.

It is the purpose of my invention to provide an underhose which is an entirety, having a complete foot and leg portion, but the toe, sole and heel portions are of a thickness or texture appreciably less than the rest of the hose and yet are knitted as a fixed part of the hose, so that the underhose will always lie smooth and yet will be comfortable to the wearer and will not unduly overheat the foot.

With these and other objects in view, the invention consists in certain novel features of construction and combinations and arrangements of parts, which will be more fully hereinafter described and pointed out in the claim.

In the accompanying drawings—

Figure 1 is a perspective view, illustrating my improved underhose;

Figure 2 is an exaggerated view in longitudinal section through the foot and lower leg portion of the hose.

1 represents the leg portion of the hose, which is of any suitable material, knitted in any desired manner, and given the proper size, shape and thickness.

2 is the foot portion of the hose. The upper half of this foot portion which cov-

ers the instep, as indicated at 4, is of the same thickness or texture as the main portion of the hose, while the main part of the foot portion, which includes a portion of the heel, sole and toe portion and extends up the sides of the foot portion the desired distance, is of appreciably thinner or lighter texture, as indicated at 3, yet is knitted as a fixed part or a continuation of the main portion of the hose.

I would call particular attention to this lighter or thinner knitted portion constituting the main foot portion of the hose as it extends substantially throughout that portion of the foot of the hose which is normally covered by a slipper, so that when a silk hose is located over the underhose there will be within the slipper a combined thickness which is little more than the average stocking has, so that there will be no undue heating of the foot and at the same time the under stocking will remain smooth, so that there will be an unwrinkled, neat appearance to both the under stocking and the outer stocking.

It is this broad idea of a complete under stocking having a toe, sole and heel portion knitted as a part of the stocking and yet thinner or lighter in weight than the rest of the stocking which constitutes the broad idea of my invention, and I do not wish to be limited to the manner of knitting the stocking or hose, the materials employed, or to any particular proportions and arrangements of the thick and thinner portions other than the thin or light portions constituting that portion of the foot covering which is normally enclosed within a shoe or slipper.

Various slight changes and alterations might be made in the general form of the parts described without departing from the invention, and hence I do not limit myself to the precise details set forth but consider myself at liberty to make such slight changes and alterations as fairly fall within the spirit and scope of the appended claim.

I claim:

An underhose having a foot portion fixed thereto, the heel, toe and lower portion of the foot of the hose being of appreciably thinner texture than the upper portion of the foot of the hose and the leg of the hose.

OWEN OSBORNE, JR.
